WASHING MACHINE

Lloyd L. Shawber and Frank Breckenridge,
Mansfield, Ohio, assignors to Westinghouse
Electric & Manufacturing Company, East
Pittsburgh, Pa., a corporation of Pennsylvania

Application April 28, 1938, Serial No. 204,712

8 Claims. (Cl. 219—38)

Our invention relates to improvements in washing machines, and more particularly to an immersion type heater and guard therefor.

During washing operations, after having filled the washing tub with water of the proper temperature, the addition of clothes thereto has the effect of lowering the temperature thereof. In addition, the water temperature is further reduced by natural heat losses due to radiation and conduction. Such lowering of temperature greatly reduces the washing efficiency of the machine. However, if the temperature of the water and wash-load be maintained at the desired value, the efficiency of the washing machine is greatly increased.

It is, therefore, an object of our invention to provide a heater which may be readily placed within the washing machine without harming the washing action thereof and which is capable of readily maintaining the wash-load and water at the desired efficient washing temperature.

A further object of our invention is to provide a removably attachable washing machine water heater which may be readily secured to the side 25 of the washing machine tub.

A further object of our invention is to provide a method of rigidly attaching the washing machine heater to the inner surface of the washing machine tub wall without drilling any additional holes therethrough or changing the construction of the machine in any manner.

A further object of our invention is to provide a washing machine heater adapted to be rigidly attached to the tub by means of the wringer post bolts which are used to attach the tub to the wringer post.

A further object of our invention is to provide a washing machine heater including a perforated shield rigidly attached thereto adapted to prevent contact with the heating element thereof and to permit the free passage of water therethrough.

A further object of our invention is to provide an immersion type washing machine heater which may be easily and readily attached to and removed from the inner wall of a washing machine tub without any rigid permanent mechanical connection therewith.

A still further object of our invention is to provide a water heater adapted for mounting within a washing tub and having a thermal-responsive device operatively associated therewith for protecting the water heater against dry operation, limiting the maximum temperature during such operation and for maintaining a

predetermined water temperature when associated with a wash-load.

Other objects of our invention will either be pointed out specifically in the course of the following description of a device embodying our invention, or will be apparent from such description.

Like reference characters indicate like parts in the several figures.

In the accompanying drawings,

Figure 1 is a perspective view of a washing machine and a heater embodying our invention attached thereto, certain parts being broken away for clearness;

Fig. 2 is a fragmentary view, partially in elevation and partially in section, of a portion of the washing machine and heater showing a method of attaching the heater to the tub wall and the wringer post;

Fig. 3 is a sectional view of the heating device embodying our invention, taken along line III—III of Fig. 4;

Fig. 4 is a sectional view taken along the line IV—IV of Fig. 3;

Fig. 5 is a partial plan and sectional view of 25 a portion of the washing machine tub and heating element showing a modified manner of attaching such heater to the tub;

Fig. 6 is a sectional view taken along the line VI—VI of Fig. 5; and

Fig. 7 is a view similar to Fig. 6 showing an additional method of attaching the heater to the side of the tub.

Referring to the accompanying drawings, we show a washing machine 10, an electric fluid or water heater 12 including a heating element 14, a supporting base 16, a thermostat 17 and a perforated shield 18, which prevents direct contact of the clothes with the element 14 but permits the free passage of water therethrough. 40 The heater 12 is in this instance attached to the washing machine 10 by means of wringer post bolts 20, but vacuum cups 22 or spring clips 24 may be employed, as hereinafter described.

The washing machine 10, which may be of any type or design desired, is shown as including a tub 26, a central agitator 27, a wringer post 30, wringer drive shaft 32 and a suitable driving motor 29, operatively associated therewith. The tub 26 is rigidly attached to the wringer post 50 30 by means of wringer post bolts 20 in a manner well known to the art, substantially as shown in Fig. 2. It is to be understood that the washing machine may be either a wringer type or a spinner type, or may be merely a washing tub. 55

However, the preferred form of heater is to be used with a washing machine having a wringer post or one having bolts already in the tub walls thereof.

5 The electric fluid or water heater 12 includes an immersion type heating element 14. The heating element 14, in this instance, comprises a tubular member having a resistance coil 13 located in the central portion thereof. The resistance coil 13 is suitably insulated from the outer sheath 15 by means of insulating material 13a in any suitable manner. However, it is to be understood that the heating element 14 may be of any immersion type heater known to the 10 art which is capable of maintaining the temperature of the water and wash-load, located within the washing machine, at a predetermined desired value, and the capacity thereof is such that it may be satisfactorily connected, with the 15 washing machine, to a common power receptacle located in a wall or elsewhere. The heating element 14 is rigidly attached to the supporting base structure 16 by being welded thereto, as shown by 34. Suitable terminals 42 extend from the 20 ends of the heating element 14 and project into the base 16 substantially as shown in Figs. 3 and 4. The terminals 42 of the heating element 14 are then in a position to be readily operatively 25 associated with a suitable flexible conductor 35, 30 within the base 16, as hereinafter described.

The base 16, as shown in Figs. 3 and 4, includes a main tubular portion 36 having an upper exteriorly threaded portion 37, and a plurality of angularly protruding portions or wings 38, either 35 integral with the tubular portion 36 or rigidly attached thereto. These wings 38 are curved longitudinally substantially the same amount as the inner surface of the tub 26, as shown in greater detail in Fig. 5. By having the wings 40 38 curved in such a manner, it is apparent that the base 16 will fit tightly against and may be rigidly attached to the inner surface of the tub wall. Apertures 40 are positioned in the wings 38 to permit cooperation with wringer post bolts 45 20, as shown in Fig. 2. However, if it be desired, the wings or protruding portions 38 may be omitted from the supporting base 16 if and when it be desired to use the vacuum cups 22 or clips 24 to support the heating element, as hereinafter 50 described.

The thermostat or thermal-responsive device 17 is positioned within the tubular portion 36 of base 16 and cooperatively associated with terminals 42 of heater 14 and conductor 35, substantially as shown in Figs. 3 and 4. A tubular insulating shield 44 should be positioned along the inner surface of the tubular portion 36 to properly insulate the terminals 42, the open end of conductor 35 and thermostat 17 therefrom. 55 The thermostat 17 may be of any adjustable or preadjusted type desired, preferably constituting a bimetallic strip 19, a stationary contact 21, and a movable contact 23, as shown in Fig. 4. However, it is preferred that such thermostat be small 60 enough to be readily positioned within base 16 and of such size and capacity as to readily control the associated heater 14. The thermostat 17 is, in this instance, inserted in one line of the heating element 14. In other words, one lead 70 of the conductor 35 is connected to one terminal of the thermostat 17 and stationary contact 21, while the other terminal or movable contact 23 of the thermostat 17 is connected to one terminal 42 of heating element 14. The second 75 terminal 42 of heating element 14 is then rigidly

attached to the second lead of conductor 35.

It is, therefore, apparent that the thermostat 17, located within the supporting base 16, will regulate and operate the heating element 14. The thermostat 17 being of any adjustable or preadjusted type desired, will regulate the operations of heater 14 so that the temperature of the water and wash-load located within the washing machine tub 26 will be maintained at the predetermined desired temperature. 10

In addition, the thermostat 17, associated with the base 16, will protect the heater against continued dry operation. This will be ensured inasmuch as the heat developed by the heater will be conveyed to the thermostat through base 16, 15 15 which, in turn, will disconnect the heater from the power supply at a predetermined temperature value, whether there is water around the heater or not. In a similar manner, the thermostat 17 will maintain the wash-load and water associated 20 therewith at a predetermined temperature value.

It is, therefore, obvious that the thermostat 17 operatively associated with the water and wash-load, and water-heater, will protect such heater against dry operation, will limit the maximum 25 temperature thereof during such operation, and will maintain a predetermined water temperature when associated with a wash-load.

Inasmuch as the water heater 12 is to be located within the washer tub 26 and the top portion thereof may be subjected to splashing of the washing fluid, it is important that a water-tight seal be maintained about the conductor 35 at the upper end of the supporting base 16. This water-tight seal is maintained by the cooperative action of a packing gasket 46, preferably rubber, and a packing nut 48, which is threadedly engaged with the threaded portion 37 of the base 16. The upper end of packing gasket 46 should extend along the cord 35 such distance that it 40 will project outside the tub 26, substantially as shown in Figs. 2 and 7. A washer 50 should be placed upon the upper end of the supporting base 16, adjacent to or on top of packing washer 51, to cooperate with the rubber packing gasket 46 45 and to center the conductor 35 in the tubular portion 36 of base 16.

The water-tight seal is effected by positioning the gasket 46 upon the conductor 35 and within the inwardly extending packing nut 48. The 50 packing nut 48 is then threadedly engaged with the threaded portion 37 of base 16 and is screwed or tightened down along such portion. As the packing nut 48 progresses along the threaded portion 37, the inwardly extending enlarged portion 49 of the packing nut 48 pulls the rubber packing gasket 46 downwardly against rigidly supported washer 50 whereby the tapered 55 cooperating surfaces of the gasket 46 and nut 48 cause the inner surface of the basket to be tightened against the cable 35. It, therefore, follows that the further down the packing nut 48 be screwed on the threaded portion 37, the tighter 60 this cooperative action between the nut 48, gasket 46 and conductor 35, will be, which in turn produces an adequate water-tight seal between the conductor 35 and the base 16.

The gasket washer 51, positioned between base 16 and washer 50, is also compressed between the 70 two members, effecting a water-tight seal therebetween. This is an additional precaution to prevent moisture from entering the base 16 along the threaded portion thereof which cooperates with packing nut 48.

It will be understood, however, that any other suitable water-tight seal for the heating element may be employed.

The shield 18 is preferably formed from perforated sheet metal. The perforations 25 are of such size as to prevent the clothing placed within the washer from passing therethrough, but to permit the free passage of the water therethrough. The smooth configuration of the 10 shield 18 is such that it does not contact the heater 14 and will not deter the washing operations of the washing machine 10 in any manner whatsoever.

In the preferred construction, the perforated 15 shield 18 is positioned about the heating element 14 and base 16 as the water heater 12 is rigidly attached to the tub 26 by means of wringer post bolts 20. The bolts 20 are inserted through apertures 41 in the shield 18 and aperture 40 in the 20 wings or protruding portions 38 of base 16, and then through the tub 26 to draw the shield 18, base 16 and tub 26 tightly against the wringer post 30. The bolts 20, therefore, rigidly attach the heater 12 to the inner surface of the tub 26 25 without any additional clips or holding devices, and without changing the shape or drilling additional holes in the side of the tub wall. With the heater 12 attached to the inner surface of the 30 washing machine tub 26 in such a manner, it is apparent that the heater 12 may be rigidly attached thereto at any time, whether it be done at the shop or in the field.

With the perforated shield 18 rigidly attached to and positioned over the base 16 and heating 35 element 14, it is obvious that any clothes positioned within the tub 26 or the person of an operator of such machine, cannot come in direct contact with the heating element 14 so as to burn or injure either the clothes or the operator. In 40 addition, the perforations located in the shield 18 permit the ready passage of the washing fluid therethrough so as to maintain the temperature thereof at the predetermined set value of the thermostat 17.

45 It will be appreciated that the washing action of the agitator 27 causes a continual flow of water past the heater body 14, so that the temperature of the main body of water is maintained substantially the same as that of the water immediately in contact with the heater body, whereby a proper setting of the thermostat maintains the desired temperature in the main body of water.

If desired, the heater 12 may be removably 55 attached to the inner surface of the washing machine tub wall 26 through the use of spring clamps or clips 24 rigidly attached to the heater 12. The spring clamps 24, as shown in Figs. 5 and 6, are of an elongated distorted U-shape, 60 having one end thereof rigidly attached to the base 16 with the other end adapted to be positioned over the top of the tub along the outside wall thereof. The clamps 24 are attached to the wings or protruding portions 38 of the base 16 65 by means of screws 54 which are operatively associated with apertures 40. However, if desired, the clamps 24 may be rigidly attached to base 16 by welding, or in any other manner. The perforated shield 18 may be positioned over the base 16 in 70 a manner as hereinabove described, with the apertures 41 thereof in line with apertures 40 of the base 16. The spring clips 24 are then positioned in line with apertures 40 and 41 and the set screws 54 inserted through the clips 24, 75 shield 18 and operatively engaged with the base

16. The screw 54 will then rigidly attach the shield 18 and clips 24 to the base 16. A rubber washer or padding 52 may be located on the inner surface of the other or free end of the spring clips 24 to cooperate with the outer surface of 5 the tub 26 and to prevent the clips 24 from marring such surface.

With a heater and spring clips arranged in such a manner, it is a simple matter for an operator to position the water heater within the 10 tub by merely biasing the free ends of the clips 24 outwardly over the outer edge of the tub 26 and forcing the heater down inside the tub. The spring clips 24 will then draw the heater 12 15 tightly against the inner side wall of the tub, whereas the rubber padding 52 will prevent the clip from marring the outer surface of the tub. If desired, an additional rubber padding 53 may be placed upon the inner surface of the supporting base 16 to prevent the heater 12 from marring 20 the inner surface of the tub. (This rubber padding 53 may, of course, be applied to all modifications of the heater.)

If desired, the heater 12 may be removably attached to the inner surface of the washing 25 machine tub 26 by means of a plurality of vacuum cups 22, one of which is shown in Fig. 7. These cups 22 are associated with the supporting base 16 so as to adequately support the heater, and, if desired, one or more additional cups 22a 30 may be attached to the lower end of the shield 18 as an additional support. With the use of the vacuum cups, it becomes necessary to rigidly attach the perforated shield 18 to the base 16 in an additional manner, inasmuch as the protruding portions or wings 38 of base 16 may be eliminated. Accordingly, it is preferred that the shield 18 be rigidly attached to the packing nut 48 35 by means of a plurality of screws 56 substantially as shown in Fig. 7. However, it is to be understood that the shield 18 may be rigidly attached 40 to the base 16 in any desired manner.

The vacuum cups 22 and 22a are rigidly attached to the shield 18 by means of screws 58 and 60, respectively. The upper vacuum cup 22 45 is attached to the shield 18 by means of the screw 58, whereas the lower vacuum cup 22 is rigidly attached to the shield 18 through the use of a sleeve 62 and screw 60. The vacuum cups 22 50 may then rigidly attach the water heater 12, including the shield 18 and base 16, to the inner surface of the tub 26 by having the operator merely place the heater in the desired position and press thereagainst, whereby the air within the vacuum cups will be expelled, in accordance 55 with well-known principles, causing such cups to tightly adhere to the inner tub surface and retaining the heater in the desired position.

It, therefore, follows that when using a water heater embodying our invention with a washing machine or washing tub, such heater through the 60 cooperative action of a suitable power supply (not shown) and the thermostat 17, will maintain the water temperature at the desired value by adding thereto the amount of heat lost due 65 to the introduction of the clothing to the water and the loss of heat due to conduction and radiation therefrom. The heater will then, through the use of the thermostat, maintain the water temperature at substantially a constant desirable 70 value, insuring a maximum efficiency of operation 75 of the washing machine.

It is to be understood that any removable immersion heater attachable to the sides of the washing tub to maintain the water temperature at a predetermined value, whether removably 75

or rigidly attached thereto, are to be included as equivalents of the device embodying our invention.

Various further modifications may be made in 5 the device embodying our invention without departing from the spirit and scope thereof, and we desire, therefore, that only such limitations shall be placed thereon as are imposed by the prior art and the appended claims.

10 We claim as our invention:

1. A washing machine comprising, in combination, a washing tub including an upstanding wall, a post, means for connecting the tub to the post, a fluid heater for supplying heat to a washing fluid contained within the tub, said heater being adapted to be attached to a vertical inner surface of the tub wall and to have substantially 15 its entire heating surface in contact with the fluid therein, and means for attaching the heater 20 to the tub wall.

2. A washing machine comprising, in combination, a washing tub including an upstanding wall, a fluid heater for supplying heat to a washing fluid contained within the tub, said heater 25 being adapted to be removably attached to a vertical inner surface of the tub wall and to have substantially its entire heating surface in contact with the fluid therein, and means for removably attaching the heater to the tub wall.

30 3. A washing machine comprising, in combination, a washing tub including an upstanding wall, a fluid heater for supplying heat to a washing fluid contained within the tub, at least one vacuum cup attached to the heater, said heater 35 being adapted to be removably attached to the inner surface of the tub wall and to be in contact with the fluid therein, and means including the vacuum cup for removably attaching the heater to the tub wall.

40 4. An electric water heater for washing machines comprising, in combination, an immersion heating element, a tubular supporting base rigidly attached thereto, a plurality of vacuum cups, adapted to connect the heater to the washing 45 machine, at least one of said vacuum cups being rigidly attached to the base, an insulated electric conductor operatively associated with the heating element, a gasket operatively associated with the conductor, a packing nut operatively associated 50 with the base and gasket for effecting a rigid water-tight connection between the conductor and heating element, a perforated shield rigidly attached to the base adapted to prevent 55 contact with the heating element and to permit the free passage of water therethrough, and a thermostat operatively associated with the conductor and heating element for regulating the operation of the heating element.

5. A washing machine comprising, in com-

bination, a washing tub including an upstanding wall, a fluid heater for supplying heat to a washing fluid contained within the tub, said heater being adapted to be removably attached to a vertical inner surface of the tub wall and to have 5 substantially its entire heating surface in contact with the fluid therein, and means for removably attaching the heater to the tub wall, an agitator located within said tub, and means comprising the agitator for maintaining a flow of fluid past 10 the heater so that the temperature of the main body of the washing fluid is maintained substantially the same as that of the fluid immediately in contact with the heater.

6. A washing machine comprising, in combination, 15 a washing tub including an upstanding wall, a structure extending substantially vertically alongside the exterior surface of said wall, a fluid heater disposed alongside the interior surface of said wall, and means for securing both 20 said structure and said heater to said wall.

7. A washing machine comprising, in combination, 25 a washing tub including an upstanding wall, a structure extending substantially vertically alongside the exterior surface of said wall, 23 a fluid heater disposed alongside the interior surface of said wall, said wall having an aperture 30 therein intermediate said structure and said heater, and means extending through said aperture for securing both said structure and said heater to said wall.

8. In a heating appliance for a clothes washing machine having a tub defined by a bottom wall and an upstanding side wall for retaining washing fluid and having a movable element 35 disposed in the tub for effecting a washing action upon the clothes, said movable element being spaced from said side wall of the tub and said tub having an access opening in its upper portion for the ingress and egress of clothes to be 40 washed, the combination of an elongated heating element having a configuration simulating the inner contour of the side wall of the tub, said heating element being insertable into the tub and removable therefrom through the access 45 opening in the upper portion of the tub, and means for readily and detachably supporting said heating element in closely spaced relation with the side wall of the tub and clear of the movable element, said heating element and its 50 supporting means being so arranged that the heating element is entirely confined in the space closely adjacent the side wall of the tub with substantially its entire heating surface in contact with the washing fluid normally disposed in 55 the tub.

LLOYD L. SHAWBER,
FRANK BRECKENRIDGE.
